UNITED STATES PATENT OFFICE.

JESSE L. HINDS, OF SYRACUSE, NEW YORK, ASSIGNOR TO THE ELECTRIC ENGINEERING AND SUPPLY COMPANY, OF SAME PLACE.

LAMP-SOCKET.

SPECIFICATION forming part of Letters Patent No. 466,288, dated December 29, 1891.

Application filed July 23, 1891. Serial No. 400,498. (No model.)

To all whom it may concern:

Be it known that I, JESSE L. HINDS, of Syracuse, in the county of Onondaga, in the State of New York, have invented new and useful 5 Improvements in Lamp-Sockets, of which the following, taken in connection with the accompanying drawings, is a full, clear, and exact description.

My invention relates to improvements in 10 incandescent-lamp sockets of the same general class as shown in my pending applications, Serial Nos. 400,499 and 400,450, filed conjointly herewith, and has for its object the 15 production of a simple and effective device which possesses a maximum degree of efficiency and durability and is manufactured at a minimum cost.

To this end it consists, essentially, in a non-conductor base-plate, a terminal-carrying 20 bracket secured to the base and adapted to support the lamp; a U-shaped bracket also secured to the base-plate and provided with a second terminal, a circuit opening and closing spring interposed between the base-plate 25 and bracket and formed with a laterally-extending arm having an outwardly-turned engaging end, a cam for rocking said spring-arm, a spindle having one extremity connected to said cam with a loose motion between the two 30 and the other formed with a laterally-extending shoulder, and a hand-piece formed with a depressed shoulder adapted to engage the laterally-extending shoulder of the spindle.

The invention furthermore consists in a 35 porcelain base-plate and a porcelain hand-piece and in the detail construction and arrangement of the parts, all as hereinafter more particularly described, and pointed out in the claims.

40 In describing my invention reference is had to the accompanying drawings, forming a part of this specification, in which like letters indicate corresponding parts in all the views.

45 Figure 1 is a vertical sectional view of my improved socket; Fig. 2, an elevation of one end of a lamp adapted to be secured to said socket. Fig. 3 is an elevation of the detached internal parts of the lamp-socket shown at 50 Fig. 1. Fig. 4 is a horizontal sectional view taken on line 44, Fig. 1. Fig. 5 is a vertical

sectional view taken on line 55, Fig. 3. Figs. 6, 7, and 8 are respectively isometric perspectives of the contact-spring, the U-shaped bracket for supporting the cam-spindle, and the inner terminal of the lamp-socket adapted to engage the lamp-collar carrying the corresponding lamp-terminal. Fig. 9 is an isometric perspective of the bracket secured to the insulator base-plate for supporting the 60 second insulator-plate. Figs. 10 and 11 are respectively isometric perspectives of the top and bottom faces of the insulator base-plate. Fig. 12 is an isometric perspective of the top face of the second insulator-plate. Fig. 13 is 65 an isometric perspective of the detached socket secured to the second insulator-plate for supporting the lamp. Fig. 14 is a vertical sectional view of the upper portion of the outer case of the lamp-socket, taken in a plane 70 at substantially right angles to that of Fig. 1; and Fig. 15 is an inverted plan view of the detached top wall of said outer shell.

A represents the outer shell of the socket, consisting of the side or peripheral wall a, 75 the top wall a', and the bottom wall a''. Projecting from the top wall a' is the nipple a³, formed with the projecting flange a⁴, extending beyond the inner face of the top wall a', and with screw-threads on its interior wall 80 adapted to receive a suitable screw-threaded support. (Not necessary to show or describe.)

a⁵ is a brace formed with a ring a⁶, which encircles the flange a⁴, and outwardly-extending arms a⁷, having their ends arranged on 85 the inner face of the upper extremity of the peripheral wall a. The inner extremity of the nipple a³ is upset at a⁸ upon the ring or collar a⁶ and is thus prevented from turning, as clamp-screws a⁹, Fig. 14, are passed through 90 openings formed in the depending flange of the top wall a', the upper extremity of the side wall, and in the extremities of said arms a⁷.

The bottom wall a² of the outer shell A is formed with a shoulder A', adapted to bear 95 against the bottom edge of the side or peripheral wall a, and is provided on its interior with screw-threads A², adapted to engage like screw-threads on a socket, presently described, secured to the internal parts of the 100 lamp for firmly securing together the outer shell and the internal parts of the lamp.

socket and for receiving and supporting the lamp.

The insulator-base B is preferably composed of porcelain, as it is a perfect non-conductor, and even though subjected to severe use does not burn or char, as is the case with some non-conductors, as vulcanized fiber.

Formed in the peripheral edge of the porcelain base B, as seen at Figs. 10 and 11, are 10 slots b for receiving the lower extremities of the arms a¹, and projecting inwardly from said slots are the recesses b', adapted to receive the inner ends of the clamp-screws a², which, in addition to securing together the 15 top and side walls of the shell, also support the base-plate by engagement with said recesses.

C is a bracket (best seen at Figs. 1, 2, 5, and 9) consisting of a pair of oppositely-arranged 20 arms c and a ring c'. The arms c are formed with feet c², which rest upon the lower face of the plate B and are firmly secured thereto by screws c³, having their shank engaged with said feet and their head with a depressed shoulder b⁴ of a socket b⁵ in the top face of 25 the base-plate B. Upon one arm c is a lug C', which carries a retaining-screw C² for one of the electric wires, which passes through a groove C⁴ in the periphery or side of the insulator-base, then along a groove C⁵ in the top face of said base, and outwardly through the 30 nipple a³. Supported upon the ring c' is a second plate D, formed of suitable insulating material, and preferably porcelain, since the same is particularly durable, as previously 35 stated. The plate D is formed with a hub d, registered with the central opening of the ring c', and with a horizontal annular shoulder d', adapted to rest against the lower face 40 of said ring.

E, Figs. 1, 2, 5, and 13, represents a lamp-supporting socket having at its upper extremity a flange e, provided with lugs e', aligned with lugs c⁴ of the ring c' and adapted to receive clamp-screws e², which are passed 45 through said insulator-plate D, and the feet c⁴ and e' for securing together the bracket C, the insulator-plate D, and the socket E, and for transmitting the electricity from the bracket C to said metallic socket, which, as previously stated, is engaged and drawn into 50 position by the ring or bottom wall a² of the shell A.

The upper extremity f of the lamp F (shown 55 at Fig. 2) is formed with a screw-threaded outer metallic collar f', adapted to be screwed within the socket E, and thus be brought into contact with the metallic shell E and make an electrical connection with one of the lamp- 60 terminals f². The other lamp-terminal f³ is connected to the inner collar f⁴ of the lamp, which is separated from the outer collar by insulating material f⁵, and is adapted to be engaged by the corresponding socket-terminal G, which consists, preferably, of a sheet-metal plate passed through an opening D' in the insulator-plate D, with one end g formed

with a depressed surface g', adapted to encounter the ring f¹. The opposite end g² of the sheet-metal plate lies on the upper face 70 of the insulator-plate D and is secured in position by a clamp-screw g³.

H represents a U-shaped bracket secured to the bottom face of the insulator base-plate by screws h, having their shank engaged with 75 said plate and their head with a depressed shoulder formed in a socket h' in the top face of the insulator-plate.

Projecting downwardly from the base of the bracket H is a lug H', that receives a retaining-screw H² for the opposite electric wire, which also passes through a peripheral groove C⁴ and a top groove C⁵ in the insulator base-plate, and thence through the nipple a³.

I is a spring formed, preferably, of a double-U shape, with one extremity i supported on the base-plate B, being preferably inserted in a slot or groove B' and interposed between the base-plate B and the bracket H in order that for the sake of economy the same screw 90 that holds the bracket H to the plate B may also retain the spring I in operative position. This spring I is formed with an arm i², extending downwardly in a substantially vertical plane on the outside of the vertical arm h² of the bracket H, and is provided with a laterally-extending arm i³, having the outwardly or downwardly bent engaging end i⁴ formed with the contact-foot i⁵ for making contact with the upper extremity g² of the terminal G. Lateral movement of the spring-arm i³ is prevented by means of lugs h⁴, depending from one of the arms h² and engaging the opposite edges of said spring-arm. The spring-arm i³ is forced into engagement with the terminal G by means of a cam J, having oppositely-arranged cam-teeth j, adapted to engage the base of said arm. 105

The spindle K for supporting and rocking the cam is journaled at its opposite extremities in the opposite arms h² of the bracket H, and is provided at its inner extremity with a lug or lugs k, mounted in a slot j', which is formed in the outer face of the cam J and is of greater width than the diameter of said 115 lug k, for connecting the spindle and cam together with a lost motion in order that the breakage of the circuit may be sufficiently quick to prevent burning of the parts.

L represents the hand-piece for operating 120 the spindle K without danger of receiving the electric shock. This hand-piece is also composed of porcelain for the reasons previously stated, and also because it presents a neat and finished appearance.

Although porcelain is so well fitted as a hand-piece for electric switches, no such hand-piece has to my knowledge been used, as it has been impossible to practically attach the same. This difficulty is, however, overcome 125 by my invention, since, as best seen at Figs. 1 and 4, the hand-piece is formed with an aperture l for receiving the spindle and with a socket l', which is of greater width in one

plane than the aperture and is formed with a depressed shoulder l^2 . The extreme end of the spindle extends slightly beyond the shoulder l^2 and is swaged or bifurcated, so as to lie upon the same, and thus firmly retain the porcelain hand-piece in position. The extremity of the spindle may be previously split before the hand-piece is mounted thereon, and by the entrance of a proper swaging-tool may be then firmly secured in position.

The operation of my invention will be readily perceived from the foregoing description and upon reference to the drawings, and it is evident that the parts are simple in construction and when operatively assembled form an effective and practical socket, which may be produced at a minimum cost, as the greater number of the parts are produced from sheet metal.

It is evident that the detail construction and arrangement of the parts of my lamp-socket may be somewhat varied without departing from the spirit of my invention. Hence I do not limit myself to its exact detail construction.

Having thus fully described my invention, what I claim as new, and desire to secure by Letters Patent, is—

1. In combination, a base-plate B, a bracket H, secured to the base-plate and formed with an arm h^2 , adapted to carry one of the socket-terminals, the herein-described double-U-shaped spring I, having one end fixed and formed with an arm i^2 , extending at the outer side of the bracket-arm h^2 , a laterally-extending arm i^3 , extending outwardly from the arm i^2 , and an engaging end i^4 , extending downwardly from the arm i^3 , a cam for engaging the spring-arm i^3 and forcing its engaging end i^4 into contact with the corresponding lamp-terminal, and a spindle loosely connected to said cam for operating the same, substantially as and for the purpose set forth.

2. In combination, a base-plate, a bracket secured to the base-plate and adapted to carry one of the socket-terminals, an arm h^2 , extending outwardly from the bracket and formed at its end with the opposite lugs $h^4 h^4$, a spring having one end engaged with the base-plate, an arm i^2 on the spring disposed on the outer face of the bracket-arm h^2 , an arm i^3 on the spring extending laterally from the arm i^2 between the lugs $h^4 h^4$, an engaging end i^4 on the spring extending downwardly from the arm i^3 and formed with a laterally-engaging foot i^4 , a cam for engaging the arm i^3 of the spring and forcing its engaging end i^4 into contact with the corresponding lamp-terminal, and a spindle loosely connected to said cam for operating the same, substantially as specified.

3. The herein-described handle for switches, the same comprising an insulating hand-piece formed with a depressed socket opening from its outer face and formed of greater diameter in one plane than that at right angles thereto and formed with a central aperture

leading from the inner face of the hand-piece to said socket, and a spindle having its outer extremity passed through said aperture into the socket and upset upon the inner shoulder of said socket for preventing contact of the hand with said spindle extremity and independent rotation of the hand-piece, substantially as set forth.

4. The combination, with a supporting-plate D, having an aperture therethrough, and the terminal G, consisting of a U-shaped plate having one end g^2 on one side of the plate D and the other g^3 passed through said plate and adapted to be engaged with the corresponding lamp-terminal, of a base-plate, a spring-arm mounted on said base-plate, and a cam for rocking the same into engagement with the terminal for opening the circuit, substantially as and for the purpose set forth.

5. The combination, with an outer shell, of a base-plate B, a bracket having one extremity secured to the base-plate and the other formed with a ring, a second plate provided with a hub inserted through said ring, a terminal secured to the second plate and adapted to engage the corresponding lamp-terminal, a U-shaped bracket secured to the base-plate, a spring supported on the base-plate and formed with a flexible laterally-extending arm adapted to engage said terminal, and a cam for tensioning the arm, substantially as described.

6. In combination, a non-conductor base-plate, a bracket having arms provided with laterally-extending feet secured to the base-plate, a ring at the opposite extremity of said bracket having inwardly-extending lugs, a second non-conductor plate mounted upon the ring, a lamp-supporting shell having an inwardly-extending flange resting upon the plate, clamps passed through said plate and engaged with the lugs of said bracket and the flange of said ring, and a terminal supported on the plate, substantially as set forth.

7. In combination, a non-conductor base-plate, a bracket having arms provided with laterally-extending feet secured to the base-plate, a ring at the opposite extremity of said bracket having inwardly-extending lugs, a second non-conductor plate mounted upon the ring, a lamp-supporting shell having an inwardly-extending flange resting upon the plate, clamp-screws passed through said plate and engaged with the lugs of said bracket and the flange of said ring, a terminal supported on the plate, a spring having one extremity secured to the base-plate and the other adapted to engage said terminal, and a cam for forcing said spring and terminal into contact with each other, substantially as specified.

8. In combination, a non-conductor base-plate, a bracket having arms provided with laterally-extending feet secured to the base-plate, a ring at the opposite extremity of said bracket having inwardly-extending lugs, a second non-conductor plate mounted upon

the ring, a lamp-supporting shell having an inwardly-extending flange resting upon the plate, clamps passed through said plate and engaged with the lugs of said bracket and the 5 flange of said ring, a terminal supported on the plate, a spring having one extremity secured to the base-plate and the other adapted to engage said terminal, a cam for forcing said spring and terminal into contact with 10 each other, a spindle connected to said cam with a loose motion between the two and formed with a laterally-extending shoulder at its extremity, and a hand-piece secured to

the extremity of the spindle and formed with a shoulder depressed below the top face for 15 engaging the shoulder on its spindle, substantially as described.

In testimony whereof I have hereunto signed my name, in the presence of two attesting witnesses, at Syracuse, in the county of 20 Onondaga, in the State of New York, this 19th day of June, 1891.

JESSE L. HINDS.
